ELECTRON TUBE

Donald F. Drieschman, Los Altos, Calif., assignor
to Eitel-McCullough, Inc., San Bruno, Calif., a
corporation of California

Application July 5, 1952, Serial No. 297,207

2 Claims. (Cl. 313—270)

1

My invention relates to an electron tube of the type having coaxial terminals, and more particularly to improvements in the envelope structure of such tubes.

It is among the objects of my invention to provide an improved vacuum tube envelope construction incorporating ceramic parts.

Another object is to provide a simplified stem structure for such a tube.

A further object is to provide an envelope of the character described for a tube having planar type electrodes.

The invention possesses other objects and features of advantage some of which, with the foregoing, will be set forth in the following description of my invention. It is to be understood that I do not limit myself to this disclosure of species of my invention as I may adopt variant embodiments thereof within the scope of the claims.

Referring to the drawing, the single figure is an axial sectional view of a tube embodying the improvements of my invention.

In greater detail, the triode type of tube illustrated comprises an anode 2, grid 3 and cathode 4 having active surfaces disposed in parallel planes. Metal anode 2, preferably of copper, at the upper end of the tube envelope has an inwardly projecting portion having a flat end face presented interiorly of the envelope and an outwardly projecting portion carrying a suitable cooler 6. The anode also carries the metal exhaust tubulation 7 which communicates with the envelope through passage 8, the tubulation being pinched off at tip 9 after evacuation of the envelope.

Cathode 4 at the lower portion of the envelope is of the indirectly heated type and comprises a cup-shaped metal sleeve having a flat upper surface coated with a suitable electron emissive material. The heater 11 for the cathode comprises a coil disposed within the cathode sleeve and is preferably surrounded by a suitable heat shield 12. Grid 3 is of the disk type having parallel wire bars lying between the anode and cathode.

Coaxial metal terminals, also preferably of copper, are provided on the envelope for the anode and grid, the anode terminal generally designated 13 being cup-shaped and the grid terminal generally designated 14 being tubular in shape. These terminals are separated and electrically insulated by a ceramic cylinder 16 metallically bonded at 17 to the anode terminal and at 18 to the grid terminal. These ceramic-to-metal seals are made by using metalizing and

brazing techniques as hereinafter described. The cup-shaped anode terminal which is secured to anode 2 has a cylindrical flange 19 forming a contact surface and has a re-entrant bottom wall providing a recess for receiving the ceramic wall cylinder 16. The tubular grid terminal 14 has a contact surface 21 and at the upper end a cupped flange 22 for receiving the ceramic cylinder.

10 Cathode stem generally designated 23 comprises a cylindrical ceramic stem member 24 coaxial with grid terminal 14 and projecting downwardly from the lower end of the envelope. This stem member is hollowed out at the lower end 15 to provide a cylindrical recess 26 and also has a bore 27 extending from the recess into the envelope. A ceramic supporting ring 28 surrounds the stem member at a point adjacent the grid terminal and is metallically bonded to stem member 24 at joint 29.

15 The whole stem structure is so designed that the cathode may be completely mounted on the stem and the entire unit inserted into the tube through grid terminal 14. For this purpose the 20 cathode stem includes a metal sleeve 31 which fits the grid terminal. Sleeve 31 is preferably of 25 copper and is preferably U-shaped with an inner edge brazed to ceramic supporting ring 28 at 32 and with an outer edge registering with the lower 30 edge of the grid terminal. Cathode sleeve 4 is 35 fitted over the inner end of stem member 24 for support and one end of the heater coil 11 is fastened to the sleeve 4. The other end of the heater is supported by a metal lead 33 which extends downwardly through bore 27 to a mounting button 34.

35 Cathode terminal 35 is formed by metalizing the outer cylindrical surface of ceramic stem member 24, which metalized area connects with the metallic bond at joint 29 so that the latter 40 serves as a lead-in conductor for the cathode. The metalized area also extends upwardly along the stem member to make contact with the cathode sleeve 4, thus completing the cathode circuit 45 into the tube.

Heater terminal 36 is formed by metalizing the inner cylindrical face of hollow stem member 24, which metalized area extends upwardly in the recess to provide a surface to which mounting button 34 can be brazed. A heater terminal is thus provided coaxial with the other electrode terminals so that the tube can readily be plugged into a socket.

55 Grid 3 is supported by a cylindrical metal mount 37, also preferably of copper, having a

skirt adapted for insertion into the grid terminal 14 and lying between the latter and the cathode stem supporting sleeve 31. The three registering edges are then simultaneously bonded together at braze 38.

The ceramic used in making up the envelope sections may be of any suitable ceramic-like material such as the alumina or zircon type ceramic bodies. I have had good success with the alumina body because it is easy to metalize and has good mechanical strength and thermal resistance properties.

The ceramic-to-ceramic joint 29 and the several ceramic-to-metal joints may be made in several ways using known metalizing and brazing techniques. For example, the ceramic pieces may be coated with finely divided metal powders such as molybdenum or a mixture of molybdenum and iron or the like, and fired in hydrogen to a temperature sufficient to sinter the metal powder to the surface of the ceramic. This produces a thin metallic layer tightly knitted to the ceramic. The sintered areas are then preferably electroplated with a metal such as nickel. Such metalized surfaces may then be brazed together or to adjacent metal parts with silver solder or brazing alloys such as silver-copper, gold-copper or the like. The brazes are readily made by fitting the parts together with rings of wire solder adjacent the joints, and then elevating the temperature of the whole up to the melting point of the solder or brazing alloy in a suitable furnace. Another metalizing technique is to paint titanium or zirconium hydride powders on the surfaces of the ceramic parts and fire in vacuum to about 1200° C. after which the metalized ceramics may be brazed with silver solder or the like.

I prefer the sintered and plated procedure of metalizing the ceramics because the plating produces a solid metal face which is excellent for brazing and also ideal for external terminal surfaces such as the terminals 35 and 36.

My improved tube is extremely rugged and will withstand high temperature operation without failure of the envelope. Where metal terminals are employed, such as the grid and anode terminals, the use of copper brazed to the ceramics provides good electrical conductivity for radio frequency currents. The stem structure, which is usually the complicated part of a tube

of this kind, is considerably simplified in my structure. This comes about because of the use of ceramic parts with metalized surfaces to provide the terminals and utilizing the braze between the ceramics as a lead-in conductor. The simplified stem structure eliminates many metal parts and extra joints.

I claim:

1. An electron tube comprising an evacuated envelope, a cathode in the envelope, a heater in the envelope for the cathode, a cathode stem on the envelope comprising a hollow cylindrical stem member of ceramic, a cathode terminal comprising a metalized area 10 on the outer surface of the ceramic stem member, a heater lead extending into the stem member, and a heater terminal comprising a metalized area 15 on the inner surface of the ceramic stem member, and a vacuum-tight metal partition 20 within the stem member joined to said metalized area and connected to the heater through said lead, said partition being spaced substantially from the lower end of the stem member, said last named metalized area extending 25 below the partition.
2. An electron tube adapted for insertion into a socket comprising an evacuated envelope, a cathode in the envelope, a heater in the envelope for the cathode, a cathode stem portion of said 30 envelope projecting downwardly from the main portion of the envelope and comprising a hollow cylindrical stem member of ceramic, a vacuum-tight partition within the stem member, a heater terminal comprising a metalized area 35 on the inner cylindrical surface of the ceramic stem member below said partition and electrically connected to said heater, and a cathode terminal comprising a metalized area on the outer cylindrical surface of the ceramic stem member 40 and spaced from the heater terminal solely by the intervening ceramic wall of said stem, said inner and outer metalized surfaces providing contact faces for engagement with the socket.
